US0D1013700S

(12) **United States Design Patent** (10) **Patent No.:** **US D1,013,700 S**
(45) **Date of Patent:** **** Feb. 6, 2024**

(54) **VEHICLE DISPLAY PANEL WITH USER INTERFACE**

(71) Applicant: **FORD GLOBAL TECHNOLOGIES, LLC**, Dearborn, MI (US)

(72) Inventors: **Peter Ruthenberg**, Troy, MI (US); **Mohammad Kalash**, Dearborn, MI (US)

(73) Assignee: **Ford Global Technologies, LLC**, Dearborn, MI (US)

(**) Term: **15 Years**

(21) Appl. No.: **29/719,924**

(22) Filed: **Jan. 8, 2020**

Related U.S. Application Data

(63) Continuation of application No. 29/711,393, filed on Oct. 30, 2019, now Pat. No. Des. 941,304.

CLAIM

The ornamental design for a vehicle display panel with user interface, as shown and described.

DESCRIPTION

The sole FIGURE is a vehicle display panel user interface. The dot-dot-dash broken line shows a vehicle display panel and forms no part of the claimed design. The dot-dash broken line is a boundary line that shows the bounds of the claim. The portion outside of the dot-dash broken line forms no part of the claimed design.
